US00D916813S

(12) **United States Design Patent** (10) **Patent No.:** **US D916,813 S**
(45) **Date of Patent:** **** Apr. 20, 2021**

(54) **DISPLAY PANEL OF A PROGRAMMED COMPUTER SYSTEM WITH A GRAPHICAL USER INTERFACE**

(71) Applicant: **Facebook, Inc.**, Menlo Park, CA (US)

(72) Inventors: **Kory Matthew Westerhold**, Palo Alto, CA (US); **Robin Maxime Clediere**, San Francisco, CA (US); **Patrick Joseph Roark Underwood**, Palo Alto, CA (US); **Christopher Joseph Welch**, Menlo Park, CA (US); **Mohammed Abid**, Palo Alto, CA (US); **Shali Myhanh Nguyen**, San Francisco, CA (US); **Brody Jay Larson**, San Mateo, CA (US); **Cristobal Alvaro Castilla Lacomba**, San Francisco, CA (US); **John Evans**, San Francisco, CA (US); **Ryan Freitas**, San Francisco, CA (US); **Brittany Holthus Lawrence**, San Francisco, CA (US); **Nicholas Aaron Merola**, Redwood City, CA (US); **Christine Serrone Gray**, Sunnyvale, CA (US)

(73) Assignee: **Facebook, Inc.**, Menlo Park, CA (US)

(**) Term: **15 Years**

(21) Appl. No.: **29/694,307**

(22) Filed: **Jun. 10, 2019**

Related U.S. Application Data

(63) Continuation of application No. 29/631,316, filed on Dec. 28, 2017, now Pat. No. Des. 857,725.

CLAIM

What is claimed is the ornamental design for a display panel of a programmed computer system with a graphical user interface, as shown and described.

DESCRIPTION

The FIGURE is a face view of a display panel of a programmed computer system with a graphical user interface.

The broken lines in the drawings are included for the purpose of illustrating environmental structure and form no part of the claimed design.
